PUMP

Hanns Hornschuch, Easton, Pa., assignor to
 Ingersoll-Rand Company, New York, N. Y., a
 corporation of New Jersey

Application August 20, 1942, Serial No. 455,397

2 Claims. (Cl. 103—109)

This invention relates to pumps, and more particularly to centrifugal pumps of the multi-stage type.

It is an object of this invention to provide an economical form of balanced multi-stage pump.

Another object of the invention is to provide a pump in which the volutes of the pump are so arranged that the pressures within the volutes, developed by certain impellers, are partly counterbalanced by the pressures on the outside developed by the other pump stages. The result of this arrangement is that the metal in the casings can be relatively thin, thereby effecting a very material saving in the cost of the pump.

Another object of the invention is to produce a relatively simple form of pump capable of being readily dismantled and accessible for repairs.

Other objects and advantages of the invention will be in part obvious and in part pointed out hereinafter.

In the drawings showing a preferred embodiment of the invention and in which similar reference characters refer to similar parts,

Figure 1 is a side elevation of a pump, constructed in accordance with the practice of the invention,

Figure 2 is an elevation looking at the inlet end of the pump of Figure 1, and

Figure 3 is a longitudinal vertical section along the line 3—3 of Figure 2 looking in the direction of the arrows.

Referring to the drawings, the pump is provided with an outer casing formed in two parts 10 and 11, generally cup shaped and joined together at peripheral flanges 12 and 13 formed integrally with the casing halves 10 and 11 respectively.

Within the casing formed by the two halves 10 and 11 is rotatably supported, a shaft 14 upon which are keyed or otherwise suitably mounted the impellers 15, 16, 17 and 18 which, in the order named, are the first, second, third and fourth stage pressure producing elements. Such impellers are formed with any suitable type of blading, as is well known to those skilled in the art of centrifugal pumps. In this instance, the forces acting on the impellers balance because of the alternate facing of the impellers with respect to each other.

The shaft 14 is provided at its ends with bearings 19 and 20 of any suitable description. The bearing 19 is formed integrally with a bracket 21 supported on a lateral extension 22 of a stuffing box 23. Likewise, the bearing 20 is provided with

a bracket 24 supported by a lateral extension of the stuffing box 25.

At its outer extremity, the casing half 10 is provided with a cylindrical aperture 26 to receive a corresponding cylindrically shaped portion 27 of the stuffing box 23, held in place therein by means of bolts 28. The joint so formed is rendered fluid tight by a suitable gasket 29 compressed by tightening the bolts 28.

The impellers 15, 16, 17 and 18 are mounted on shaft 14 in any suitable manner, preferably being held in proper spaced relationship by spacers as, for instance, between impellers 15 and 18 there is provided a spacing sleeve 30 and between impellers 16 and 17 a similar sleeve 31.

At the inlet side of the impeller 15 is provided a spacer 32 and a shaft sleeve 33 held in place by suitable nut 34, packing being provided between the shaft sleeve 33 and the spacer 32 as shown at 35. Similarly, at the inlet side of the impeller 16 is provided a spacer 36 and a shaft sleeve 37 held in place by a nut 38, packing being provided as shown at 39.

Packing 43 is provided for the shaft within a suitable recess 40 and is compressed between the flanged bushing 41 and a gland 42. In this instance, the shaft packing 43 is of the metallic type.

The casing half 11 is provided with a stuffing box 25, in this instance exactly like the stuffing box 23 and the shaft 14 at the adjacent portion and may be packed in exactly the same fashion at the opposite end of the casing. Accordingly, the casing half 11 is provided with an aperture 45, also preferably cylindrical as is the aperture 26. It will be noted that the aperture 45 is of sufficient diameter to permit withdrawal of the impeller 16 therethrough. Likewise, the aperture 26 is of sufficient size to permit the passage therethrough of the impeller 15.

In accordance with this invention, passages are provided within the casing to transfer liquid pumped by the impellers from a suitable inlet connection 46 to a discharge connection 47. To this end the inlet connection 46 is in the form of a tube provided with a flange 44 for attachment to a suitable external pipe (not shown) and is formed integrally with the casing half 10. It communicates with an internal passageway 48 having a wall 49 formed integrally with the casing half 10 and extending about the shaft 14. In the wall 49 is provided a stepped bore 50 to receive the complementary stepped periphery of an internal wall or ring 51 formed integrally with the stuffing box 23 and supported thereon by

webs as shown at 52. Within the ring 51 is a bore 53 forming a running fit with the impeller 15 to prevent leakage of fluid under pressure back into the inlet passage formed in the stuffing box 23 by ring 51.

An additional wall 54, preferably also formed integrally with the casing half 10 forms with the outer wall a chamber 55, into which fluid is adapted to be discharged from the volute 56 associated with impeller 15. The chamber 55 extends into the casing half 11 where it is formed by the outer wall of that casing and inner wall 56' formed integrally therewith. Chamber 55 communicates with the inlet of the second stage impeller 16, which is also provided with a volute 57 leading to a chamber 58 within the wall 56'.

Chamber 58 is bounded by diaphragm 59 cast integrally with wall 56' and a second diaphragm 60, also formed integrally with that wall. Chamber 58 communicates with the inlet of impeller 17 which is provided with a discharge chamber 61 associated with the volute 62 for the impeller 17 and also with the inlet of the impeller 18.

Chamber 61 is completely inclosed within the walls 56' and 54 so that the pressure within the chamber 61 is partly counter-balanced by the external pressure in chamber 55. Volute 63 of the last stage impeller 18 is likewise completely inclosed within the chamber 61 and is adapted to discharge through an aperture 63' associated with the discharge connection 47 by means of a passageway 64 cast integrally with the casing half 10.

It will be noted that to provide access to the impeller 18 a removable diaphragm 65 is provided between the impellers 17 and 18, it being held in place by suitable studs 66.

The pump is preferably mounted on a base plate 67 there being suitable laterally extending arms 68 provided on the casing half 10 supported by pedestals 80. A dowel 69 locates the casing laterally and longitudinally with respect to the base plate 67.

Expansion of the pump casing is permitted and the outboard end of the pump is steadied by an upright flexible plate member 70 attached to the base plate 67 by means of a suitable foot piece 71 and also attached at its upper end to the stuffing box 25 by a suitable stud 72.

In the making of casing halves 10 and 11 the chambers 55, 58 and 61 are cored and the walls thereof are therefore supported by suitable webs 82 for the sake of rigidity.

The hereinabove described arrangement is especially suitable for service such as pumping hot oil, or where the pump has to be occasionally dismantled either for cleaning or replacement of parts. It will be noted that the pump can be completely dismantled without removing the casing half 10 from the base and without disturbing the external connections to the inlet and discharge nozzles 46 and 47.

Upon removal of the bearing 20 and the adjacent shaft packing, the stuffing box 44 can be removed to provide access to the impeller 16. 65 This will permit removal of the impeller 16 and, if desired, the entire casing half 11 may be removed by unbolting at the flanges 12 and 13.

Access to the impeller 18 is provided by removing the studs 66 which hold the diaphragm 65 in place, whereupon that impeller may be withdrawn from the shaft. Likewise, the stuffing box 23 may be removed through the aperture 26 and, if desired, the impeller 15 may be pulled from the shaft through the aperture 26 and the shaft removed in the opposite direction.

A still further advantage of this construction is the lightness of the casing. It will be noted that the chamber 55, which acts as a transfer passage from the first stage impeller 15 to the second stage impeller 16 almost completely incloses the passageways associated with the other stages. The outer walls of the casings 10 and 11 may, therefore, be of relatively thin section. Furthermore, the shaft packings are not subjected to extremely high pressures and are relatively easily maintained tight.

The inner walls, as for instance 56' and 54, may also be constructed of relatively light sections, since the outer pressure in the chamber 55 counteracts the inside pressure to a considerable degree. Furthermore, the chambers 58 and 61 are relatively smaller, which also tends to permit lighter wall sections. The same principle is carried still further by the inclosure of the volute or diffusor 62 within the chamber 61. Thus the highest pressure, which is within the volute 62, is minimized in its effect on the walls of the volute by the relatively counter-balancing high pressure in the chamber 61. There is provided a succession of higher pressures from the outside to the interior, the highest pressure being contained in a chamber surrounded by pressure fluid from the next highest stage.

I claim:

1. In a pump, a series of impellers arranged in pairs symmetrically with respect to a central plane, a shaft for supporting said impellers, a casing housing said impellers and vertically split adjacent said plane, and shaft stuffing boxes removable from the ends of said casing to permit removal of the outer impellers from the casing, said casing being provided with a passageway to conduct fluid between the outer two impellers and enveloping the inner impellers, said stuffing boxes being provided with passageways forming inlets to said outer impellers.

2. In a pump, a series of impellers arranged in pairs symmetrically with respect to a central plane, a shaft for supporting said impellers, a casing housing said impellers and vertically split adjacent said plane, shaft stuffing boxes removable from the ends of said casing to permit removal of the outer impellers from the casing, said casing being provided with a passageway to conduct fluid between the outer two impellers and enveloping the inner impellers, said stuffing boxes being provided with passageways forming inlets to said outer impellers, and a central diaphragm in a face of one half of said casing removable to permit withdrawal of one of said inner impellers therefrom.

HANNS HORNSCHUCH.
